Attorney

UNITED STATES PATENT OFFICE.

ROLANDIS A. BLAIR, OF FORT WAYNE, INDIANA, ASSIGNOR TO THE P & M COMPANY, OF CHICAGO, ILLINOIS, A CORPORATION OF ILLINOIS.

RAIL ANCHOR.

Application filed January 10, 1925. Serial No. 1,520.

To all whom it may concern:

Be it known that I, ROLANDIS A. BLAIR, a citizen of the United States, residing at Fort Wayne, in the county of Allen and State of Indiana, have invented certain new and useful Improvements in Rail Anchors, of which the following is a specification.

My invention relates to devices for preventing the longitudinal creep of railroad rails, these devices being commonly called rail anchors, anti-creepers or rail stays.

One of the objects of my invention is the provision of a rail anchor of simple and compact construction, inexpensive to manufacture, which will maintain a reliable hold on the rail as against the tendency of the device to become loosened by vibration or other disturbing influences, and which may be quickly and conveniently put in place on the rail, or removed therefrom, should occasion require.

A further object of my invention is the provision of a rail anchor so constructed that it may be removed and replaced several times without impairing its holding power.

Another object of my invention is the provision of a rail anchor so constructed that it can be used with rails having bases differing in width, thickness or contour.

It is another object of my invention to provide a rail anchor adapted to prevent the longitudinal creep of railroad rails in both directions.

In its preferred form my invention contemplates a rail base embracing yoke member having inwardly extending lips adapted to bear on the respective top surfaces of the rail base flanges and a depending portion adapted to extend transversely under the rail base, said depending portion having flanges projecting laterally from its respective sides; and a further object of my invention is the provision of a U-shaped resilient key adapted to straddle the depending portion of the yoke member and to be driven between the under face of the rail base and said laterally projecting flanges, said key being so shaped that it has to be distorted when it is driven home, for example, the legs of the key may be arranged so that normally they stand out of alignment with respect to each other.

The invention consists in the novel arrangements, constructions and devices to be hereinafter described and claimed for carrying out the above-stated objects and such other objects as will appear from the following description of a preferred embodiment illustrated in the accompanying drawings, wherein—

Fig. 1 is a perspective view of a rail anchor embodying the principles of my invention shown in operative position on a fragmentary portion of a rail base;

Fig. 2 is a side elevational view illustrating the manner in which the yoke member of the device may be applied to the rail base;

Fig. 3 is a side elevational view showing the yoke member in operative position on the rail base and the key member about to be driven into place;

Fig. 4 is a side elevational view of the resilient key; and

Fig. 5 is an end elevational view, on a reduced scale, showing the device in operative position on the rail and abutting against a tie.

Like characters of reference designate like parts in the several views.

The yoke member 7 of the device is provided with inwardly extending lips 8 and 9, the under surfaces of which are adapted to bear on the respective top surfaces of the rail base flanges 10 and 11, and a depending portion 12 which extends substantially transversely of the rail base when the yoke member is in operative position thereon. Flanges 13 and 14 project laterally from the respective sides of the depending portion 12. The depending portion 12 is under-cut or notched at 15 to provide for application of the yoke member to the rail base as will be presently explained. The yoke member is preferably punched or cut out of a rolled steel bar of T-shape in cross section.

The key means 16, employed in association with the yoke member, is preferably made out of a bar of resilient, relatively high-carbon steel and in the present embodiment comprises a U-shaped member formed so that its legs 16^a and 16^b may straddle the depending yoke portion 12 when the key is driven in place. As clearly shown in Fig. 4, the legs of the key normally stand

out of alignment, in the present case the leg 16^a occupying a position lower than that occupied by the leg 16^b.

In applying the device to a rail the yoke member is first placed substantially transversely of the rail base in the position shown in dotted lines in Fig. 2 wherein it will be noted that the edge of the rail base flange 11 extends into the notch 15 which permits the inner edge of the lip 8 to clear the edge of the rail base flange 10 when the other end of the yoke member is raised. The yoke member is then shifted transversely on the rail base into a position substantially as shown in full lines in Fig. 2 whereupon it may be lowered on the rail base with the under surfaces of the lips 8 and 9 bearing on the respective top surfaces of the rail base flanges 10 and 11 as shown in Fig. 3. The key is then inserted, as shown in Fig. 3, with its legs straddling the depending yoke portion 12, the respective legs 16^a and 16^b being disposed between the under face of the rail base and the upper faces of the flanges 13 and 14 of the yoke member. A tool such as a sledge or the like is then used to strike the connected end of the key (left end, Fig. 3) to drive the key transversely of the rail and the yoke member into the position shown in Fig. 1.

The key in being driven home is considerably distorted, the two legs of the key being forced into substantial alignment which sets up a twisting strain in the key and results in the device taking and maintaining a reliable grip on the rail base, the lips 8 and 9 exerting a powerful downward pressure on the tops of the respective rail base flanges while the upper edges of the legs of the key exert a powerful upward pressure against the bottom of the rail base. Since the key is appreciably distorted when driven home on the yoke member there is a powerful and reliable binding action between the bottom edges of the legs of the key and the respective flanges 13 and 14 which, combined with the binding action between the upper edges of the legs of the key and the under side of the rail base, is ample to prevent the key from working backwardly on the yoke member. The grip of the device on the rail base is ample to prevent any slippage thereof longitudinally of the rail in either direction, notwithstanding the disturbing influences to which the device is subjected due to the passage of heavy rolling stock and changeable weather conditions.

The device can be used with rails having bases differing in width, thickness or contour due to the fact that the key means is considerably distorted in driving it home. For rails beyond the limit of adjustment of any given key the device may be adapted without changing the yoke member by merely using a key having narrower or wider

legs. Due to the fact that the legs of the key straddle the depending portion of the yoke member and that the lines of contact between the legs and the rail base are widely separated, there is little chance for the device to rock or tilt on the rail under a creeping strain. The device is of simple and compact construction and inexpensive to manufacture. It may be conveniently and quickly put in place on a rail. The holding power of the device compared to the amount of metal used in it is very great. The device may be readily removed from the rail by striking the free or non-connected ends of the legs of the key and driving the key backwardly on the yoke member. The device may be reapplied to a rail, in fact it may be removed and replaced several times without impairing its holding power.

I do not intend to limit my invention to the details of construction shown and described, except only in so far as certain of the appended claims are specifically so limited, as it will be obvious that modifications may be made without departing from the principles of my invention.

I claim:

1. A rail anchor comprising a rail base embracing yoke having a subjacent portion normally horizontally disposed with respect to the under face of the rail and a resilient key adapted to be driven transversely of the rail between the under face of the rail base and said subjacent portion of the yoke.

2. A rail anchor comprising a rail base embracing yoke and a resilient U-shaped key adapted to straddle a portion of the yoke and to be driven transversely of the rail between the underface of the rail base and a subjacent portion of the yoke.

3. A rail anchor comprising a rail base embracing yoke having a subjacent portion normally horizontally disposed with respect to the under face of the rail and a resilient key adapted to be driven transversely of the rail between the under face of the rail base and said subjacent portion of the yoke, said key being of such shape that it is distorted when it is driven home, for the purpose specified.

4. A rail anchor comprising a rail base embracing yoke and a resilient U-shaped key adapted to straddle a portion of the yoke and to be driven transversely of the rail between the under face of the rail base and a subjacent portion of the yoke, said key being of such shape that it is distorted when it is driven home, for the purpose specified.

5. A rail anchor comprising a rail base embracing yoke and a resilient U-shaped key, the legs of which are normally out of alignment, adapted to be driven transversely of the rail between the under face of the rail base and a subjacent portion of the yoke.

6. A rail anchor comprising a rail base

- embracing yoke and a resilient U-shaped key, the legs of which are normally out of alignment, adapted to straddle a portion of the yoke and to be driven transversely of the rail 5 between the under face of the rail base and a subjacent portion of the yoke.
7. A rail anchor comprising a rail base embracing yoke provided with a transversely extending depending portion having flanges 10 projecting laterally from its respective sides and resilient key means adapted to be driven between the under face of the rail base and said flanges.
8. A rail anchor comprising a rail base 15 embracing yoke provided with a transversely extending depending portion having flanges projecting laterally from its respective sides and a resilient U-shaped key adapted to straddle said depending portion and to be driven between the underface of the rail base and said flanges.
9. A rail anchor comprising a rail base 20 embracing yoke provided with a transversely extending depending portion having flanges projecting laterally from its respective sides and resilient key means adapted to be driven between the under face of the rail base and said flanges, said key means being of such shape that it is distorted when driven home, for the purpose specified.
10. A rail anchor comprising a rail base 25 embracing yoke provided with a transversely extending depending portion having flanges projecting laterally from its respective sides and a resilient U-shaped key adapted to straddle said depending portion and to be driven between the under face of the rail base and said flanges, said key means being of such shape that it is distorted when driven home, for the purpose specified.
11. A rail anchor comprising a rail base 30 embracing yoke provided with a transversely extending depending portion having flanges projecting laterally from its respective sides and a resilient U-shaped key adapted to straddle said depending portion and to be driven between the under face of the rail base and said flanges, said key being of such shape that it is distorted when driven home, for the purpose specified.
12. A rail anchor comprising a rail base 35 embracing yoke provided with a transversely extending depending portion having flanges projecting laterally from its respective sides and a resilient U-shaped key, the legs of which are normally out of alignment, adapted to straddle said depending portion and to be driven between the under face of the rail base and said flanges.
13. A rail anchor comprising a yoke member 40 having inwardly extending lips adapted to bear on the top surfaces of the respective rail base flanges and a depending portion adapted to extend transversely under the rail base, said depending portion having flanges 45 projecting laterally from its respective sides, and resilient key means adapted to be driven between the under face of the rail base and said last named flanges.
14. A rail anchor comprising a yoke member 50 having inwardly extending lips adapted to bear on the top surfaces of the respective rail base flanges and a depending portion adapted to extend transversely under the rail base, said depending portion having flanges 55 projecting laterally from its respective sides, and resilient key means adapted to be driven between the under face of the rail base and said last named flanges. 70
15. A rail anchor comprising a yoke member 60 having inwardly extending lips adapted to bear on the top surfaces of the respective rail base flanges and a depending portion adapted to extend transversely under the rail base, said depending portion having flanges 65 projecting laterally from its respective sides, and resilient key means adapted to be driven between the under face of the rail base and said last named flanges, 75
16. A rail anchor comprising a yoke member 70 having inwardly extending lips adapted to bear on the top surfaces of the respective rail base flanges and a depending portion adapted to extend transversely under the rail base, said depending portion having flanges 75 projecting laterally from its respective sides, and a resilient U-shaped key, the 80 legs of which are normally out of alignment, adapted to straddle said depending portion and to be driven between the under face of the rail base and said last named flanges. 85
17. A rail anchor comprising a member 85 adapted to be applied to the base of a rail intermediate the ends of the rail and extend under said base and provided with a subjacent portion normally parallel to the bottom surface of the rail base, and a key 90 adapted to be driven into binding engagement with the rail and the subjacent portion of the rail base and said last named flanges. 95
18. A rail anchor comprising a member 100 adapted to engage the base of a rail and extend under said base and formed with a subjacent portion normally parallel to the bottom surface of the rail base, and a key 105 adapted to be distorted into binding engagement with the rail and the said subjacent portion of said anchor member. 110
19. A rail anchor comprising a member 115 adapted to engage the base of a rail and extend under the base and formed with a subjacent portion normally parallel to the bottom surface of the rail base, and a key 120 adapted to be distorted into binding engagement with the rail and the said subjacent portion of said anchor member. 125
20. A rail anchor comprising a member 130 adapted to engage the base of a rail and extend under the base and formed with a subjacent portion normally parallel to the bottom surface of the rail base, and a key 135 adapted to be distorted into binding engagement with the rail and the said subjacent portion of said anchor member. 140

bottom surface of the rail base, and a key having two members offset with relation to each other and adapted to be distorted into binding engagement with the rail and the subjacent portion of said anchor member.

20. A rail anchor comprising a member adapted to engage the base of a rail and extend under said base and formed with a sub-

jacent portion normally parallel to the bottom surface of the rail base, and a resilient key having two members offset with relation to each other and adapted to be distorted into binding engagement with the rail and the subjacent portion of said anchor member. ¹⁰

ROLANDIS A. BLAIR.
